UNITED STATES PATENT OFFICE.

DUGALD S. PATERSON, OF PHILADELPHIA, PENNSYLVANIA, AND GUSTAV B. PETSCHÉ,
OF YONKERS, NEW YORK.

FILLING MACHINE.

Application filed June 6, 1924. Serial No. 718,197.

Our invention relates to machines for filling cans or other receptacles with measured quantities of a liquid. The object of our invention is to provide a machine of this kind adapted for filling receptacles of various sizes and shapes with fluids of varying consistency which shall be positively accurate as to the volume of liquid delivered to each can; capable of working at great speed; so constructed as to avoid the soiling of the receptacles and machinery by drip from the delivery nozzle and so constructed as to be readily taken apart for cleaning.

The nature of our improvements will be best understood as described in connection with the drawings in which our improved machine is illustrated and in which-

Figure 1 is a side elevation of the machine.

20 Figure 2, an end elevation thereof.

Figure 3, a plan view.

Figure 4, an elevation of one side of the machine taken as on the section line 4—4 of Fig. 1.

25 Figure 5, a sectional elevation on the line 5—5 of Fig. 1.

Figure 6, a sectional elevation on the line 6—6 of Fig. 1.

30 Figure 7, a cross section in detail on the line 7—7 of Fig. 6.

Figure 8, a cross section on the line 8—8 of Fig. 6.

35 Figure 9, a sectional view of the latching device for holding the nut in position, taken as on the line 9—9 of Fig. 7.

Figure 10 is an elevation of the drip pan and mechanism for actuating it, taken partly on the section line 10—10 of Fig. 1.

40 Figure 11 is a sectional elevation taken on the line 11—11 of Fig. 10.

Figure 12 is a cross section on the line 12—12 of Fig. 10.

Figure 13 is a plan view on the section line 13—13 of Fig. 10.

45 Figure 14 is a sectional view on the line 14—14 of Fig. 13.

Figure 15 is a view taken partly on the line 15—15 of Fig. 16, showing the mechanism for adjusting and securing in place the crank pin which actuates the piston of the measuring cylinder.

50 Figure 16 is a partly sectional view taken on the line 16—16 of Fig. 15.

Figure 17 is a sectional view on an enlarged scale, taken on the line 17—17 of Fig. 1.

Figure 18 is a sectional view on the line 18—18 of Fig. 17.

Figure 19, a perspective detail.

Figure 20, a view of the delivery nozzle taken as on the line 20—20 of Fig. 17.

Figure 21 is a sectional view on the line 21—21 of Fig. 20.

Figure 22 is a detached view of the liquid seal cup as shown in Fig. 20.

Figure 23 is a plan view of the cup shown in Fig. 22.

Figure 24 is a view on a larger scale of the snap hook at the end of the eccentric rod shown in Fig. 17.

Figure 25 is a sectional view on the line 25—25 of Fig. 24.

Figure 26 is a front view of the scraper conduit used for keeping the edge and bottom of the drip pan clean.

Figure 27 is a side elevation of this device, and

Figure 28, a plan view.

Figure 29 is a plan view showing the mechanism for giving intermittent rotation to the cam supporting table showing also in plan the drip catcher.

A indicates the base plate of the machine shown as mounted on wheels A' for ready transportation. B is a standard secured to the base plate and supporting the measuring cylinder B', here shown as formed integral with the standard. B' is an opening through the lower part of the standard and B' a bracket extending out from the standard on which various parts of the mechanism, to be described, are supported. C is the cylinder head formed with slotted lugs C' by means of which and swing bolts, indicated at c', it is held in place on the head of the cylinder B', while, at the same time, made readily detachable therefrom. The cylinder head is formed with a conical plug valve seat, indicated at C², from which opens a port C³ leading to the cylinder, a port C⁴ leading through a conduit E to a supply receptacle and a port C⁵ connecting with the delivery nozzle, to be described. D, best shown in Figs. 17 and 18, is a conical three-way plug cock, fitting in the seat C² and formed with a recess D' at its outer end, from the bottom

2
of which leads a cylindrical recess D^2 forming a seat for a spiral spring. D^3 is a cap screwing into the head C , as shown, having a projecting bearing D^4 for the valve spindle 5 D^5 , which valve spindle is formed with a squared portion D^6 which fits in the recess D' of the plug valve and in which is formed the cylindrical spring seat indicated at D^7 . D^8 indicates the slotted end of the valve 10 spindle and D^9 the spring inserted in the recesses D' and D^2 . D^{10} is a lever arm secured on the slotted end D^8 of the valve spindle and holding at its end the bearing pin D^{11} .

15 F is an outlet conduit connected with the outlet port C^5 and having an open end normally closed by a plug f and extending downward from its outer end the delivery nozzle F^2 externally threaded at F^3 at its lower end, as best shown in Fig. 20. F^4 indicates the extreme downward edge of the delivery nozzle and F^5 is a cap screwing on the threaded portion F^3 and having a contracted lower end, as indicated at F^6 . 20 F^7 is a cup supported on the cap F^5 by spider extensions indicated at F^8 so that its upper edge F^8 extends around and above the lower edge F^4 of the nozzle F^2 .

25 G is the main shaft of the machine driven by a motor and gearing, generally indicated at R but not shown in detail as these features of the machine form no part of our invention. G' is an eccentric secured on the shaft G and G^2 a bevel wheel also secured on the shaft G . Also secured at the end of this shaft is the head H which lies in the opening B^2 of the standard B and is formed with a slot H' having overhanging edges, as indicated best in Fig. 15, and within which is secured the rack bar indicated at H^2 . H^3 is a scale secured on the face of the head H to aid in adjusting the crank pin to be described. I is a crank pin having a head I' which lies within the slot H' and contacts 30 with the inner face of the overhanging edges of this slot. The downwardly extending portion I^2 of the crank pin is fitted upon it, the sleeve I^5 having a flange I^6 which lies in contact with the face of the head H . The crank pin is formed with an internal bearing, as indicated at I^4 , and has its outer 35 end threaded, as indicated at I^3 . I^7 is a disc washer fitting against the outer end of the sleeve I^5 and I^8 is a nut screwing on the end of the crank pin. I^9 is a crank pin bearing fitted on the sleeve I^5 . I^{10} is the head of the connecting rod fitted on the crank pin bearing.

40 I^{11} is the connecting rod which, as shown in Fig. 5, connects with the piston I^{12} through a pin I^{12} . I^{14} is a scale indicating finger attached to the sleeve flange I^6 , as best shown in Fig. 16. J is a shaft fitting in the bearing I^4 of the crank pin and carrying on its inner end the gear wheel J' ,

which engages the rack H^2 and at its outer end the hand wheel J^2 by which the shaft and gear wheel can be rotated. K is an eccentric ring fitting on the eccentric G' and attached to the lower end of the connecting rod K' to the upper end of which is secured the snap hook head, indicated at K^2 and best shown in Figs. 24 and 25. The upper portion of the head K^2 is bored out, as indicated at K^3 , and within which are placed a spring K^4 and a latch holding slide K^7 which is pushed upward by the spring K^4 and has a head K^8 which enters the recess D^{12} in the end of the sleeve d^{10} fitting on crank pin D^{11} . The upper end 70 of K^5 of the head K^2 is formed with a hook which, as shown in Fig. 25, fits on the end of the sleeve d^{10} .

75 L is the standard on which the rotating table and the mechanisms for adjusting and operating it are supported; as shown this standard is formed with a vertical perforation L' and a bearing L^2 at its top and secured to it are the brackets L^3 and L^5 supporting the shaft bearings L^4 and L^6 . L^7 is a Geneva wheel having a bearing L^8 fitting in the bearing L^2 and L^9 is a threaded shaft extending into the perforation L' and having a head L^{10} beyond which extends a threaded portion L^{11} . To the head L^{10} is firmly secured the can supporting table, indicated at L^{12} , formed with a central upwardly extending boss L^{13} on which rests a can positioning plate, indicated at L^{14} which is clamped down on the boss L^{13} by 80 means of the wing nut, indicated at L^{15} . The threaded portion of the standard L^9 is formed with a groove l^0 , see Fig. 8, by means of which and a feather secured to the Geneva wheel bearing, the shaft is rotatably connected to this Geneva wheel and free to move longitudinally in it. M is a nut screwing on the threaded shaft L^9 and resting on the Geneva wheel, as shown in Fig. 6. Radial threaded perforations, indicated at M' , see Fig. 7, are formed in this nut into which screw handles indicated at M^2 , M^3 and M^4 , the handle on the bar M^3 , see Fig. 9, being formed hollow and supporting a longitudinally movable bar M^4 85 having a latching end M^5 which can enter the groove l^0 in the shaft L^9 and which is pressed inward to engage this groove by a spring M^8 , held in place by a head M^7 through which extends a contracted extension M^6 of the bar M^4 , having attached to it a head M^9 by which it may be drawn upward to withdraw the latch from engagement with the slot l^0 . The Geneva wheel is actuated by the wheel G^2 which engages a bevel N secured on the lower end of the shaft N' to the upper end of which are secured an arm N^2 carrying a roller pin N^3 adapted to enter the slots of the Geneva wheel and a segmental disc N^4 which oper- 90 100 105 110 115 120 125 130

ates to hold the Geneva wheel and connected parts stationary in the familiar way indicated best in Fig. 29.

G³, best shown in Figs. 10 and 11, is a bevel wheel secured to the shaft G and connected with a bevel wheel O secured on the lower end of the vertical shaft O¹ to the upper end of which is secured the bevel gear O² which has a bearing on the bracket O³ secured to the top of the bearing O⁴, as shown in Fig. 10, this bearing O⁴ being connected by a web indicated at O⁵ with a vertical tubular extension, indicated at O⁶. The casing O⁷ has a shaft bearing O⁸ formed in it which supports the shaft O⁹ to one end of which is secured the bevel gear O¹⁰ in engagement with the bevel gear O² while to its other end is secured a bevel gear O¹¹ which engages a bevel gear O¹² secured to a sleeve O¹³ supported in the tubular extension O⁶ and having a head at its upper end on which is formed a flattened portion indicated at O¹⁴, see Figs. 10 and 12. O¹⁴ is a drain tube extending through the sleeve O¹³ but not secured thereto and to the upper end of this tube is secured a head O¹⁵ which rests upon the head O¹² of the sleeve O¹³ and supports the drip catcher, indicated at O¹⁶, to which is secured the spring O¹⁷ carrying at its lower end the block O¹⁸ which it presses against the flat portion O¹⁴ of the head O¹⁵.

P is a clamping ring secured on the casing O⁶, as shown in Figs. 10 and 12 and carrying a bracket arm P' to which is secured the scraper or wiper P², see Figs. 12, 26, 27 and 28. P² indicates the scraper or wiping member edge of this device which fits against the edge and lower portion of the drip catcher O¹⁶, as shown in Fig. 10, and the scraper is formed with a bevel P⁴ by which any liquid scraped off from the drip catcher is conducted to a receptacle placed to receive it.

Q is an arm secured to the bracket B³ and carrying an adjustable finger Q' to which in turn is secured a guiding spring, indicated at Q², the function of which is to hold the cans in position on the table and in the spacing plate L¹⁴ at the time they are being charged. S is a platform secured to a projection B⁴ of the standard B on which can be placed an open-ended can to receive the drip from the drip catcher and the wiper working in connection with the drip catcher.

The operation of our machine will be easily understood from the drawings and description. It is first necessary to set the crank pin I at a proper distance from the center of the shaft G so as to regulate the stroke of the piston I¹³ in the cylinder B'. To do this the nut I⁸ is retracted on the threaded end of the pin so that the pin is no longer clamped in the slot H'. By means of the hand wheel J² the shaft J and gear wheel J'

will rotate so as to shift the pin in the slot H' and by means of the indicator finger I¹⁴ and the scale H³ the stroke of the piston is regulated so that at each stroke it will deliver the exact amount of liquid required for filling a can or other receptacle. The nut I⁸ is then screwed down with the result that the crank pin is firmly secured in position.

At each downward stroke of the piston liquid is drawn in to the cylinder B' through the inlet port C⁴ and at each upward movement of the piston an exactly measured quantity of liquid is forced out of the cylinder and in to the outlet port C⁵, the three-way plug valve D being actuated by the described mechanism in perfect synchronism with the movement of the piston and so that, irrespective of the stroke of the piston, the ports in the head C are fully opened and closed and it will be observed that as both the inlet and outlet ports communicate only with the top of the cylinder the upper part of the cylinder will always be filled with liquid with no opportunity for air to accumulate which would, of course, result in a defective delivery. It will also be observed that for purposes of cleaning, the head C of the cylinder can be promptly detached from the cylinder by loosening the bolts c' and disconnecting the snap hook K⁵ by the mechanism described in connection with Figs. 24 and 25.

The delivery nozzle forms an important feature of our invention. It is connected with the outlet passage C⁵ by the conduit F which can be readily cleaned by removing the plug F' screwed into its threaded end and this conduit F and the downwardly extending nozzle F² are maintained at all times full of liquid by means of the liquid seal provided by the cup F⁷, the edges of which, F⁸, extend above the lower edge F⁴ of the nozzle so that no air can enter the lower end of the nozzle, while the atmospheric pressure will prevent the outflow of liquid from the nozzle at any time except when liquid is being forced into the nozzle. It will also be observed that the construction described in connection with Figs. 20 to 23 provides for the ready detachment and cleaning of all the mechanical parts of the nozzle which is a matter of great importance.

It is, of course, advisable that the cans to be filled should be supported with their filling orifices close to the plane of the lower end of the delivery nozzle and it is obviously necessary that the cans should be accurately positioned on the conveyor or rotating table which brings them successively into registry with the delivery nozzle so that their filling orifices will register with the nozzle during each dwell in the movement of the table. The necessary adjustment in the height of the table is provided for by

the threaded shaft L^9 and a nut M and when it is necessary to change the height of the table the latch M^5 is withdrawn by means of the handle M^9 and the nut M rotated by means of the handles M^2 and M^3 until the shaft carrying the table L^{12} has been moved up or down to the desired point, when the latch M^5 is again engaged with the slot in the threaded shaft L^9 so that the table will remain in fixed position. The positioning plate L^{14} secured to the top of the base or pedestal L^{13} , or otherwise spaced from the top of the table, has its outer edge shaped to closely engage and position the cans resting upon the table L^{12} and where cans of different sizes and shapes are to be filled it is important that proper positioning plates should be readily attached to the table and this is provided for by the pedestal and wing nut construction illustrated in Fig. 6 and described in connection with this figure.

The drip catcher pan O^{16} is given, by the mechanism described in Figs. 10, 11 and 13, a rotative movement synchronous with relation to the movements of the can carrying table and of the movements of the piston in the measuring cylinder so that the pan will pass under a delivery nozzle only after it has delivered the measured charge into the can, the direction and speed of rotation of the drip catcher being such that some portion of it will remain under the delivery nozzle until a new can is brought by the rotating table into registry with the delivery nozzle and, to prevent breakage of the machine or of some part of it, the connection between the drip pan and its driving mechanism is made yielding so that in case the drip pan in its rotation strikes any object it can remain stationary. This is provided for in the construction shown by connecting the pan with its driving mechanism through the spring supported block O^{18} normally resting in contact with the front portion O^{12} of the rotating sleeve O^{12} .

While the drip catching pan O^{16} is made disc shaped and provided with a channel O^{14} to carry off the liquid caught in the pan, it is unavoidable that some liquid will be caught upon the edges of the pan and run down over the outside of these edges and the bottom of the pan, and to prevent such liquid from accumulating and falling on the machine or the cans, we provide the wiper or scraper P^2 with a wiping edge P^3 which fits over the outer edge and the outer bottom of the pan so as to scrape off liquid adhering to these portions and carry it off through the channel P^5 into some receptacle which may conveniently be the same receptacle with which the conduit O^{14} registers, for instance, a drip pan resting on the platform S .

The drip catcher is not secured in place otherwise than by the engagement of the

block O^{18} with the flattened portion O^{13} of the head O^{12} , and it can be readily removed for cleaning by lifting it and its attached tube O^{14} from the sleeve O^{12} .

Having now described our invention, what we claim as new and desire to secure by Letters Patent, is:

1. A filling machine having a measuring cylinder and a piston moving in said cylinder, in combination with inlet and outlet ports connecting with the cylinder at the top thereof, a downwardly extending delivery nozzle connected to the outlet port having a hydraulic seal at its lower end to prevent the entrance of air and maintain the nozzle full of liquid, adjustable means for actuating the piston whereby its stroke can be varied at will and positively actuated means for opening and closing the ports operating in timed relation to the movements of the piston.

2. In combination with a filling machine comprising a cylinder and a positively actuated piston organized to deliver a liquid to containers, a delivery nozzle having a downwardly extending portion and a cup located below the end thereof having a rim extending around and above the lower end thereof so as to form a liquid seal to prevent the entrance of air or a gravitational outflow of liquid therefrom.

3. In combination with a filling machine comprising a cylinder and a positively actuated piston organized to deliver a liquid to containers a delivery nozzle having a downwardly extending portion, a cap nozzle detachably secured to the lower end of said downwardly extending portion and a cup detachably supported on said cap nozzle with its upper edge extending around and above the lower end of the main nozzle so as to form a liquid seal therewith.

4. In a filling machine having a measuring cylinder and piston a delivery nozzle and an intermittently moving conveyor for supporting the receptacles to be filled below the delivery nozzle and successively bringing them into registry therewith, a rotary drip catcher normally moving in timed relation to the movements of the conveyor so as to extend below the nozzle while the conveyor moves to shift the containers, and means for rotating said drip catcher incorporating a yielding connection which enables the drip catcher to stand still if it meets an obstruction.

5. In a filling machine having a measuring cylinder and piston a delivery nozzle and an intermittently moving conveyor for supporting the receptacles to be filled below the delivery nozzle and successively bringing them into registry therewith, a rotary upright sleeve moving in timed relation to the movements of the conveyor, a drip catcher having a drainage tube removably supported

on said sleeve and having its drainage tube extending through the sleeve and yielding means for rotatively connecting the drip catcher and sleeve.

- 5 6. In a filling machine having a measuring cylinder and piston, a delivery nozzle and a conveyor table for supporting the receptacles to be filled below the delivery nozzle and successively bringing them into registry therewith, a rotary drip catcher nor-
- 10

mally moving in timed relation to the movements of the conveyor so as to extend below the nozzle while the conveyor moves to shift the container, and a scraper conduit arranged to wipe liquid from the edge of the drip catcher as it moves away from below the delivery nozzle and conduct it to a convenient point of delivery. 15
